(57) **CLAIM**

The ornamental design for a cell counter, as shown and described.

DESCRIPTION

FIG. 1 is a front, top perspective view of a first embodiment of a cell counter of our new design.

FIG. 2 is a front view of a first embodiment of a cell counter of our new design.

FIG. 3 is a rear view of a first embodiment of a cell counter of our new design.

FIG. 4 is a right side view of a first embodiment of a cell counter of our new design.

FIG. 5 is a left side view of a first embodiment of a cell counter of our new design.

FIG. 6 is a top view of a first embodiment of a cell counter of our new design.

FIG. 7 is a bottom view of a first embodiment of a cell counter of our new design.

FIG. 8 is a front, top perspective view of a second embodiment of a cell counter of our new design.

FIG. 9 is a front view of a second embodiment of a cell counter of our new design.

FIG. 10 is a rear view of a second embodiment of a cell counter of our new design.

FIG. 11 is a right side view of a second embodiment of a cell counter of our new design.

FIG. 12 is a left side view of a second embodiment of a cell counter of our new design.

FIG. 13 is a top view of a second embodiment of a cell counter of our new design.

FIG. 14 is a bottom view of a second embodiment of a cell counter of our new design.

FIG. 15 is a front, top perspective view of a third embodiment of a cell counter of our new design.

FIG. 16 is a front view of a third embodiment of a cell counter of our new design.

FIG. 17 is a rear view of a third embodiment of a cell counter of our new design.

FIG. 18 is a right side view of a third embodiment of a cell counter of our new design.

FIG. 19 is a left side view of a third embodiment of a cell counter of our new design.

FIG. 20 is a top view of a third embodiment of a cell counter of our new design; and,

FIG. 21 is a bottom view of a third embodiment of a cell counter of our new design.

The portions of the features depicted in broken lines are not part of the claimed design.
